M. V. VENTRELLA

AUTOMATIC LEAF TURNER

Filed May 29, 1925

UNITED STATES PATENT OFFICE.

MICHAEL V. VENTRELLA, OF BRONX, NEW YORK.

AUTOMATIC LEAF TURNER.

Application filed May 29, 1925. Serial No. 33,618.

This invention relates to improvements in automatic leaf turners for the leaves of books, particularly music books, and it is the principal object of the invention to provide a device of this character in which a foot operated, articulated finger engages pockets formed on the leaves of the book and turns the same when returned into its original position by a suitable foot pedal.

Another object of the invention is the provision of a device of this character in which the book is supported on an adjustable support carried by an adjustable and collapsible stand.

A further object of the invention is the provision of a leaf turner for music books comprising a weighted treadle, padded for making its operation noiseless, and provided with means for limiting its movements.

A still further object of the invention is the provision of a leaf turner for music books including a finger and a cam guide for the same, said finger being attached to a drum which is adjustably connected to the treadle.

It is also one of the objects of the present invention to provide a music leaf turner for books in which the book is supported by a shelf carried by an adjustable plate.

These and other objects and advantages of my invention will become more fully apparent, as the description thereof proceeds, and will then be more specifically defined in the appended claims.

In the accompanying drawing forming a material part of this disclosure:

Fig. 1 is a front elevation of a music stand equipped with a turner for the leaves of a book of music mounted thereon, constructed according to the present invention.

Fig. 2 is a side elevation thereof.

Fig. 3 is an enlarged detail view of the cam faced housing, drum and finger thereon.

Fig. 4 is a section on line 4-4 of Figure 5.

Fig. 5 is a sectional top plan view seen in the direction of the arrows 5-5, Figure 4.

Fig. 6 is a rear end view of the music book support, seen in the direction of the arrows 6-6 of Figure 2.

Fig. 7 is a detail view of a book of music having the pockets attached thereto.

Fig. 8 shows in sectional view one of the pockets.

Fig. 9 is a front elevation of a pocket.

Fig. 10 is a detail view of the developed cam outline in the drum housing.

The hollow music stand 10 is supported by foldable legs 11 and movable links 12 attached to a collar 13. Within the stand a rod 14 is vertically displaceable which can be locked in any of its adjusted positions by means of a wing bolt 15. The rod 14 carries the usual collapsible support or table 16 for the music book 17, the lower edge of which rests on a flange 18 of a support 19 attached to a plate 20 by means of buttons 21, adapted to engage recesses 22 in said plate.

This plate has a plurality of holes 23, 24 and 25 formed with elongated end slots therein through which pass buttons 26, or the like, of the frame of the support for holding the plate firmly attached thereto, if the buttons engage in the elongated end slots of the plate.

The frame bar 27 carries at its upper end, 75 a casing or housing 28 having an opening therein and formed in said opening a cam face 29 constructed so as to present at one end of the said opening, an upwardly disposed cam 29^a, and at the other end of the 80 said opening, a downwardly disposed cam 29^b.

A drum 30 is rotatably arranged within the housing on a pin 31, and has an arm 32 hingedly mounted, as generally indicated at 85 30', on one side, this hinged joint being quite tight, so that frictional forces hold the said arm stationary in whatever position it may be placed. The arm 32 has pivotally mounted on its outer end, an articulated finger 33, normally held in aligned position with the said arm, by a spring 34, which allows a bending of the finger to one side.

A cable 35 is attached at one end to the drum and is guided over a roller 36 in an 95 opening of the housing and over a roller 37 rotatably secured to an arm of plate 20. To the lower end of the cable, a chain 38 is attached the lower end of which is adjustably secured to a weighted foot pedal or treadle 39 pivotally attached on a frame 40 equipped with a padding 41 adapted to be engaged by a pad 42 on the underside of the treadle, while a bracket 43 limits the downward movement, its upper extension 43 limits the 105 upward movement of the pedal.

A spring 44 is arranged within drum 30 and has one of its ends attached to pin 31 while its other end is attached, as at 45, to the boss in the drum.

The leaves of the book have pockets 46 glued thereto adapted to receive the finger

33. These pockets 46 are strengthened by bending the front part of the material upon itself within the pocket, as indicated at 47, in Figure 8.

5 The device operates as follows:

Normally spring 44 holds the drum 30 so positioned that the arm 32 is engaged at one end of the cam opening in the housing 28, namely the end formed with the upwardly disposed cam 29^a. In this position the arm 32 is likewise upwardly inclined. If it is desired to turn one of the leaves of the book of music 17, the pedal 39 is depressed by the foot, rotating the drum 30 by the intermediary of chain 38, and cable 35, so that the arm 32 of finger 33 is caused to glide along the cam face 29. The finger 33 reaches the front face of the leaf of the book to be turned, and its motion is then arrested thereby, but the drum continues its motion until it reaches the end of the cam opening formed with the downwardly disposed cam 29^b, and the spring 34 allows a bending so that the finger can remain stationary against the face of the leaf, while the drum completes its motion. But in completing its motion the drum causes the arm to be depressed downwardly due to contact with the downwardly disposed cam 29^b, and the finger engages into the pocket 46. The operator is now ready to turn the leaf at the appropriate time by releasing the pedal 39, whereupon spring 44 turns the drum 30 towards its normal position, and at the same time the finger takes along the leaf to be turned, and near the end of the return stroke, the arm 32 engages the cam 29^a, thereby lifting the finger upwards out of engagement from the pocket, and upon completion of the return stroke, the device is in its original normal position.

It is to be understood that while I have shown and described the preferred form of my device by way of example, any size book 45 may be turned by my device. It will be understood that other such changes may be made, as fall within the scope of the appended claims, without departure from the

spirit of the invention, and the principle involved.

Having thus described my invention, what I claim as new, and desire to secure by Letters Patent, is:

1. A turner for the leaves of books, or the like, comprising a drum rotatably mounted in a housing formed with a cam opening characterized by an upwardly disposed cam portion at one end, and a downwardly disposed cam portion at the other end, an arm hingedly mounted on said drum by means of a friction tight joint, a finger pivotally secured to the front end of said arm, normally held in alignment therewith by the action of a spring fastened to one of said members and bearing against the other, and a spring co-acting between said drum and housing, normally urging said arm to the upwardly disposed cam portion of said cam opening, whereby upon turning the drum against the action of said last mentioned spring, the said arm engages against the downwardly disposed cam, and turns said finger downwards, and upon releasing the drum the finger moves back to its original position.

2. The combination, in a device of the class described, comprising a drum rotatably mounted in a housing formed with a cam opening characterized by an upwardly disposed cam portion at one end, and a downwardly disposed cam portion at the other end, an arm hingedly mounted on said drum by means of a friction tight joint, a finger pivotally secured to the front end of said arm, normally held in alignment therewith by the action of a spring fastened to one of said members and bearing against the other, whereby upon rotating the drum the motion of the finger may be arrested, while permitting a further rotation of the drum so as to allow the said arm to engage the respective cam portions.

In testimony whereof I have affixed my signature.

MICHAEL V. VENTRELLA.
